UNITED STATES PATENT OFFICE.

ELEMIR J. NEY, OF NEW YORK, N. Y., ASSIGNOR TO HARTFORD CARPET COMPANY, OF HARTFORD, CONNECTICUT.

DESIGN FOR A CARPET-PATTERN.

Specification forming part of Design No. 5,593, dated March 5, 1872.

To all whom it may concern:

Be it known that I, ELEMIR J. NEY, of the city, county, and State of New York, have invented or produced a new and original Design for a Pattern to be Inwrought into Ingrain and other Carpeting, in colors similar to those painted on the drawing or photograph accompanying this specification, or in other colors substituted in the place of those painted on the drawing or photograph herewith; and I do hereby declare that the drawing accompanying this specification does give and convey to any one skilled in the art of carpet-weaving a defined and thorough description of the nature of my invention, and is sufficient to enable any one skilled in the art of carpet-weaving to use my invention.

What I claim as my invention, and desire to secure by Letters Patent, is—

The configuration of the design hereto annexed, when applied to carpeting in the form similar to the drawing or photograph accompanying this specification.

ELEMIR J. NEY.
